UNITED STATES PATENT OFFICE.

ELECIE P. FARUM, OF OAKLAND, CALIFORNIA, ASSIGNOR TO LEO GILLIG AND CHESTER H. GILLIG, BOTH OF SAN FRANCISCO, CALIFORNIA.

SLIDING-WINDOW MECHANISM.

Application filed August 26, 1920. Serial No. 406,172.

To all whom it may concern:

Be it known that I, ELECIE P. FARUM, a citizen of the United States, and a resident of Oakland, county of Alameda, and State of California, have invented a new and useful Sliding-Window Mechanism, of which the following is a specification.

My invention relates to sliding window mechanism and particularly to means for preventing the rattle of the slideable windows such as are used on automobile tops.

An object of the invention is to provide simple and effective means for preventing the rattle of windows, which will be automatically placed in operative position or released therefrom by the movement of the sash.

Another object of the invention is to provide means of the character described which may be thrown into operative position or released therefrom at a point intermediate the extreme forward or rearward position of the sash by merely moving the latter in one direction or the other.

The invention possesses other objects and features of advantage, some of which, with the foregoing, will be set forth in the following description of the preferred form of my invention which is illustrated in the drawings accompanying and forming part of the specification. It is understood that I do not limit myself to the showing made by the said drawings and description, as I may adopt variations of the preferred form within the scope of my invention as set forth in the claims.

Referring to said drawings:

Figure 1 is a vertical section of the top of an automobile equipped with slideable windows and the mechanism of my invention. Parts of the inside lining of the top are shown broken away in order to disclose the construction more clearly.

Figure 2 is a longitudinal section of one side of the top, the plane of section being indicated by the line 2-2 of Fig. 1.

Figure 3 is a vertical section of one side of the top taken on the line 3-3 of Fig. 1.

Figure 4 is a side view of one of the members of the clamping mechanism.

Briefly expressed the mechanism as here shown comprises a window frame in which is arranged a set of sashes supported therein by hangers which slidably engage a perforated track. Clamping mechanism is ar-

ranged on the track and moves with but is normally released from clamped engagement with the sash. When, however, during the movement of the sash the proper opening or perforation in the track is encountered by the clamping mechanism, a part of the latter is permitted to pass through the opening and engage the sash. Thereafter a slight continued movement of the sash will operate to force the clamping mechanism into tight engagement therewith, thereby causing the mechanism and the hangers to be pressed against opposed surfaces of the track with a considerable force. To effect the release of the sash it is only necessary to slide it in the reverse direction. By providing a number of openings in the track the sash may be clamped in several intermediate positions. Means are also provided for enabling the clamping mechanism to pass over the intermediate openings should it be desirable to merely clamp the sash at one or the other of its extreme end positions.

A detailed description of the present embodiment of the invention follows:

The mechanism of my invention, as has been hereinbefore mentioned, is particularly adapted for use in connection with the slideable windows of automobiles and accordingly I have shown such an embodiment in the drawings. The body 2 of the automobile here illustrated is of the enclosed type and is formed with the usual top 3 having a permanent side window 4 between which and the windshield is the opening 5. The sides of the opening 5 are in the form of a frame 7 which includes pockets 8 and 9 and in which is slidably disposed a pair of sashes 11 and 12. The pocket 8 is formed between the permanent window 4 and the inside wall 13 of the top and serves to enclose the sashes 11 and 12 when they are in their rearward or open position. The pocket 9 is formed between the inner and outer walls 13 and 14 at the top of the opening 5 and extends practically the full length thereof. Fixed in the pockets 8 and 9 and spaced from the outer and inner walls thereof is a track 16 formed on its opposite sides with grooves 17 and 18 in which engage hangers 19 and 21 respectively that support the sashes 11 and 12. The sash 11 is arranged to move forward the full length of the opening 5 so that it may close the forward half thereof, whereas the sash 12 is arranged to

- move forward just sufficient to close the rear half of the opening. The sashes are prevented from moving laterally by means of the guides 22 and 23 preferably provided on the upper face of the automobile doors 24 and 25. Suitable means such as the handles 27 and 28 may be secured to the sashes in order to readily slide the latter in the frame.
- 10 Mechanism is provided for holding the sashes tightly clamped to the track both at their extreme end positions as well as at an intermediate position, which will permit the clamping or releasing of the sash, whether at 15 the end or intermediate position by the continued or reverse movement of the sash. Fixed to each sash for longitudinal movement therewith but slidably transversely thereof is a clamping member 29 preferably 20 disposed between the hangers and arranged in the grooves of the track. In the present embodiment of the invention part of the necessary transverse movement of the clamping member is permitted by forming it of a 25 resilient material but it is obvious that such movement may be permitted by mounting it yieldingly. Formed in the lower face 30 of both grooves 17 and 18 of the track are a plurality of longitudinally spaced openings 31 in which may enter, so as to effect the 30 clamping of the sash in a manner which will be hereinafter described, one of a pair of arms 32 that is pivoted to the member 29. The arms are preferably pressed by a 35 spring 33 so that the free ends thereof which are provided with anti-friction rollers 34 will normally bear against the faces 30. The arm 35 which is pivoted to the clamping member associated with the sash 11 is adapted 40 to engage either the openings 37 or 38 thereby allowing the sash 11 to be clamped in its extreme forward position or intermediate position respectively. The other arm 39 of this set is adapted to engage the opening 41 so that the sash 11 may be clamped 45 in its extreme rear position. In a practically similar manner the arms 42 and 43 of the member 29 associated with the sash 12 are adapted to engage the openings 44 and 50 45 respectively and thereby clamp the sash 12 in its extreme forward and rearward position respectively. By arranging the arms so that the roller will always precede the pivoted end of the arm when the sash is 55 moved, and by sloping the sides of the openings downwardly in the direction of motion of the sash, the leading arm will readily engage such an opening whereas the arm which follows will readily pass over it. In accordance with the foregoing, as clearly seen in Figure 1, the sides of the openings 37, 38 and 44 are sloped downwardly and forwardly whereas the sides of openings 41 and 60 45 slope downwardly and rearwardly. 65 The operation of the mechanism is as fol-

lows: Assuming that it is desired to move the sash 11 from a rear position to the position shown in Figure 1, the sash is moved forward so that the arm 35 on reaching the opening 38 enters it and comes in contact 70 with the top of the sash. When the arm first contacts with the sash top it is forced to assume a position in which its longitudinal axis lies substantially parallel to the sides 75 of the opening. This is due to the fact that the upper surface of the clamping member is already in contact with the upper face 47 of the track groove and thereby prevents the arm from becoming fully extended. However upon the continued movement of the 80 sash the arm abuts against the forward side of the opening and causes the clamping member to flex sufficiently to enable the free end of the arm to lie back of a vertical line 85 intersecting its pivotal point—in which position the clamping mechanism is locked. To release the sash from its clamped engagement with the track it is merely necessary to move the sash in the reverse direction thus causing the arm and clamping member to go 90 through the previous movements in the reverse order.

The top of the sash at the point where the rollers of the arms engage is provided with a plurality of plates 48, one or more of which 95 may be added or removed should it be desired to vary the tension with which the sash is clamped to the frame.

Means are provided for preventing the entrance of the arms in the intermediate opening 38 when it is desired to clamp the sash in its extreme forward position. As here shown the said means comprises a plate 49 which is slidably mounted in the lower wall of the track so that it can be moved to close 100 the top of the opening and thereby prevent the entrance of the roller, as the arm during the movement of the sash, passes over the opening. The plate 49 is provided with a handle 51 which is disposed to one side of 105 the path of the sash 11.

While I have shown but one intermediate opening 38 it is obvious that the number can be increased in accordance with the number of intermediate positions it may be desired to clamp the sashes.

I claim:

1. In combination with a window frame, a track provided in said frame and having an aperture formed therein, a sash slidable 120 longitudinally in said frame, a hanger engaging said track and supporting said sash, and sash clamping mechanism carried by said sash for longitudinal movement therewith adapted to project through said track 125 aperture and force said hanger in tight engagement with said track.

2. In combination with a window frame, a track provided in said frame and having an opening formed therein, a sash slidable longi- 130

tudinally in said frame, a hanger engaging said track and supporting said sash, and sash clamping mechanism slidably arranged on said track and movable with said sash 5 adapted to project through said opening and engage and clamp said sash against movement.

3. In combination with a window frame, a track provided in said frame and having an 10 opening formed therein, a sash slidable longitudinally in said frame, a hanger engaging said track and supporting said sash, a transversely movable yielding clamping member slidably arranged on said track and 15 movable longitudinally with said sash, and an element provided on said clamping member adapted to project through said opening to engage said sash whereby said hanger and clamping member may be forced in tight 20 engagement with the track.

4. In combination with a window frame, an internal double faced track provided therein and having an opening in one of said faces, a sash slidable longitudinally in said 25 frame, a hanger supporting said sash and engaging said track between said faces, a transversely movable yielding clamping member carried by said sash for longitudinal movement therewith and slidably arranged between the faces of said track, and an arm connected to said clamping member 30 arranged to bear upon the perforated face of the track and adapted to pass into the opening therein and tightly engage the sash.

5. In combination with a window frame, an internal double faced track provided in said frame and having an opening in one of said faces, a sash slidable longitudinally in said frame, a hanger supporting said sash 35 and engaging said track between said faces, a transversely movable member carried by

said sash for longitudinal movement therewith and slidably arranged between the faces of said track, and an arm pivoted to said member arranged to ride upon said perforated face of the track and adapted to have its free end pass through the opening therein and engage said sash and the side of the said opening whereby continued longitudinal movement of the sash will operate to 45 throw said end from one side to the other of a vertical line intersecting the pivotal point of said arm and said member.

6. In combination with a window frame, a track provided with upper and lower inner 50 faces and having an opening in the lower face, a sash slidable longitudinally in said frame, a hanger supporting said sash and engaging the lower inner face of said track, a transversely movable yielding member 55 slidably arranged in said track between said faces and fixed to said sash for longitudinal movement therewith, an arm pivoted to said member and arranged to ride upon said perforated face of the track, the free end of said 60 arm being adapted to enter the track opening and engage said sash and the side of the opening whereby continued longitudinal movement of the sash will operate to cause said arm to assume a substantially vertical 65 position and thereby force said yielding member and said hanger in tight engagement with said upper and lower faces respectively, and means for pressing the free end of said arm against said lower face. 70

In testimony whereof, I have hereunto set my hand at Oakland, California, this 20th day of August, 1920.

ELECIE P. FARUM.

In presence of:—

L. L. M. SALSBURY.
